DESIGN FOR A CONCRETE BURIAL VAULT COVER

Wilbert W. Haase, Forest Park, Ill., assignor to
Wilbert W. Haase Co., Forest Park, Ill., a cor-
poration of Illinois

Application May 3, 1937, Serial No. 69,135

Term of patent 14 years

To all whom it may concern:

Be it known that I, Wilbert W. Haase, a citizen of the United States of America, residing at Forest Park, in the county of Cook and State of Illinois, have invented a new, original, and ornamental Design for a Concrete Burial Vault Cover, of which the following is a specification, reference being had to the accompanying drawing, forming a part thereof.

Referring to the drawing:

Figure 1 is a plan view of a concrete burial vault cover showing my new design.

Fig. 2 is an enlarged side elevational view thereof broken away and contracted to show both ends thereof; and

Fig. 3 is an end elevational view thereof.

I claim:

The ornamental design for a concrete burial vault cover, as shown.

WILBERT W. HAASE.
